TOY ELECTRICAL SIGNALLING DEVICE

Allan Ross, University City, Mo., assignor to Bell Products Company, St. Louis, Mo., a corporation of Missouri

Application November 8, 1954, Serial No. 33,030

Term of patent 3½ years

(Cl. D34—15)

FIG. 1.

FIG. 2.

FIG. 3.

FIG. 4.

FIG. 5.

FIG. 6.

Fig. 1 is a top plan view of a toy electrical signalling device, showing my new design;

Fig. 2 is a side elevational view thereof;

Fig. 3 is a front elevational view thereof;

Fig. 4 is an opposite side elevational view thereof;

Fig. 5 is a rear elevational view thereof; and

Fig. 6 is a bottom plan view thereof.

I claim:

The ornamental design for a toy electrical signalling device, substantially as shown.
